CLAIM

The ornamental design for a swaddle, as shown and described.

DESCRIPTION

FIG. 1 is a front view of a swaddle showing the new design with the arm holes open.

FIG. 2 is a front view thereof with the arm holes closed.

FIG. 3 is a front view thereof with the arm holes open in use on an infant.

FIG. 4 is a front view thereof with the arm holes closed in use on an infant.

FIG. 5 is a back view thereof with the arm holes open; and,

FIG. 6 is a back view thereof with the arm holes closed. The broken lines depict unclaimed portions and form no part of the claimed design. Any portions not visible in the drawings form no part of the claimed design.
